UNITED STATES PATENT OFFICE.

CORWILL JACKSON, OF KALAMAZOO, MICHIGAN.

TAMPER AND LIKE IMPACT-TOOL.

1,399,387.

Specification of Letters Patent.

Patented Dec. 6, 1921.

Application filed April 11, 1921. Serial No. 460,557.

To all whom it may concern:

Be it known that I, CORWILL JACKSON, a citizen of the United States, residing at Kalamazoo, Kalamazoo county, Michigan, have invented certain new and useful Improvements in Tamers and like Impact-Tools, of which the following is a specification.

This invention relates to improvements in tamers and like impact tools. I have, in the embodiment illustrated, shown my improvements as adapted by me for tie tamers although the structure illustrated with proper modification in the tool proper is adapted for use in other relations.

The main objects of this invention are:

First, to provide an improved impact tool of the class described which is highly efficient and very convenient to use.

Second, to provide an improved impact tool of the class described which enables the performance of a large amount of work with a little effort on the part of the user.

Further objects, and objects relating to structural details, will definitely appear from the detailed description to follow.

I accomplish the objects of my invention by the devices and means described in the following specification. The invention is clearly defined and pointed out in the claims.

A structure which is the preferred embodiment of my invention is clearly illustrated in the accompanying drawing forming a part of this specification, in which:

Fig. I is a side elevation of an impact tool embodying the features of my invention.

Fig. II is a detail view mainly in central longitudinal section on a line corresponding to line 2--2 of Figs. III and V.

Fig. III is a detail transverse section on a line corresponding to line 3--3 of Figs. I, II and IV.

Fig. IV is a detail section through the tool holder on a line corresponding to line 4--4 of Figs. I and II.

Fig. V is a detail transverse section on a line corresponding to line 5--5 of Fig. II.

In the drawing similar reference characters refer to similar parts throughout the several views, and the sectional views are taken looking in the direction of the little arrows at the ends of the section lines.

Referring to the drawing I provide a casing-like body 1 provided with bearings 2 in the ends thereof for the motor shaft 3. Mo-

tor 4 is shown conventionally. On the driving or motor shaft 3 is an impact wheel 5 having a tappet 6 set into the periphery thereof. The impact wheel 5 is provided with a dove-tailed seat 7 for the tappet 6, the tappet being slightly tapered longitudinally and retained in the seat by the wedge 8. A tool holder 9 projects laterally from the casing in alinement with the impact wheel.

The tool 10, which in the structure illustrated is a tamping bar, is reciprocatingly mounted in the tool holder to project into the casing into coacting relation with or in position to receive the blows from the tappet 6. An impact bar 11 is provided for the tool 10, the tool having a collar 12 adapted to engage the impact bar. The impact bar is supported by the bolts 13 arranged through the lugs 14 on the tool holder, coiled springs 15 being seated on these lugs for supporting bolts 13. A spring 16 is seated on the collar 12, the upper end of the spring being seated on the internal shoulder 17 in the tool holder. This spring normally holds the tool out of the path of the tappet. The collar 13 limits the upward travel of the tool so that its inner end does not bear against the impact wheel but is engaged by the tappet when the tool is resting on the ballast or under pressure from the handle.

The handle bar 18 is resiliently connected to the casing 1 preferably by the spring members 19 and 20. The spring member 19 is S-shaped, one end of the spring being rigidly secured to the casing which is provided with the lugs 21 slotted at 22 to receive the spring attaching bolts 23. The spring 20 is bowed and engaged with a pin 24 disposed in alinement with the shaft 3.

By thus mounting the handle the operator is relieved from shocks and vibrations of the tool, and the tool is supported so that there is a lateral as well as a longitudinal movement to its tool which is particularly desirable in the tamping of ties.

I have not illustrated the various types of tools which may be used as these would vary according to the kind of work to be performed.

Having thus described my invention, what I claim as new and desire to secure by Letters Patent is:

1. In a structure of the class described, the combination of a casing-like body member

- 2
- having a laterally projecting tool holder disposed at one end, a tool reciprocatingly mounted in said tool holder, an impact bar for said tool, a supporting spring for said bar, a driving shaft provided with bearings in the ends of said body member, impact wheel on said shaft provided with a tappet coacting with said tool, a handle comprising an S-shaped spring having one end rigidly secured to the tool holder end of said casing, a bowed spring pivotally secured to the other end of said casing, and a handle bar on the outer ends of said springs, and a spring normally holding said tool out 15 of the path of the tappet.
2. In a structure of the class described, the combination of a casing-like body member having a laterally projecting tool holder disposed at one end, a tool reciprocatingly 20 mounted in said tool holder, a driving shaft provided with bearings in the ends of said body member, impact wheel on said shaft provided with a tappet coacting with said tool, and a handle comprising an S-shaped 25 spring having one end rigidly secured to the tool holder end of said casing, a bowed spring pivotally secured to the other end of said casing, and a handle bar on the outer ends of said springs.
3. In a structure of the class described, the combination of a casing-like body member having a laterally projecting tool holder disposed at one end, a tool reciprocatingly 30 mounted in said tool holder, an impact bar for said tool, a supporting spring for said bar, a driving shaft provided with bearings in the ends of said body member, impact wheel on said shaft provided with a tappet coacting with said tool, a handle having a 35 resilient connection to said casing, and a spring normally holding said tool out of the path of the tappet.
4. In a structure of the class described, the combination of a casing-like body member having a laterally projecting tool holder disposed at one end, a driving shaft provided with bearings in the ends of said body member, impact wheel on said shaft provided with a tappet, a tool reciprocatingly 40 mounted in said tool holder to be engaged by said tappet, and handle having a resilient connection to said casing.
5. In a structure of the class described, the combination of a body member provided 45 with a tool holder, a tool reciprocatingly mounted in said tool holder, an impact bar for said tool, a supporting spring for said bar, a driving shaft provided with bearings on said body member, impact wheel on said 50 shaft coacting with said tool, and a handle comprising an S-shaped spring having one end rigidly secured to one end of said cas-
- ing, a bowed spring pivotally secured to the other end of said casing, a handle bar mounted on the outer ends of said springs, and a spring normally holding said tool out of the path of the tappet.
6. In a structure of the class described, the combination of a body member provided with a tool holder, a tool reciprocatingly 55 mounted in said tool holder, a driving shaft provided with bearings on said body member, impact wheel on said shaft coacting with said tool, and a handle comprising an S-shaped spring having one end rigidly secured to one end of said casing, a bowed spring pivotally secured to the other end of said casing, and a handle bar mounted on the outer ends of said springs.
7. In a structure of the class described, the combination of a body member provided with a tool holder, a tool reciprocatingly 60 mounted in said tool holder, an impact bar for said tool, a supporting spring for said bar, a driving shaft provided with bearings on said body member, impact wheel on said shaft coacting with said tool, and a handle having a resilient connection to said body member, and a spring normally holding said tool out of the path of the tappet.
8. In a structure of the class described, the combination of a body member, a tool reciprocatingly mounted on said body member, an impact wheel coacting with said tool, and a handle comprising an S-shaped spring 65 one end of which is secured to said body member, a bowed spring pivotally secured to the opposite end of said body member, and a hand piece mounted on the outer side of said springs.
9. In a structure of the class described, the combination of a body member, a tool mounted on said body member, an impact wheel coacting with said tool, a spring normally holding said tool out of the path of the tappet, and a handle having a resilient connection to said body member.
10. In a structure of the class described, the combination of a body member, a tool mounted on said body member, an impact wheel coacting with said tool, a handle for said tool, and a spring normally holding said tool in inoperative position, the tool being brought into coacting relation with the impact wheel by pressure on the tool as in holding it to the work.
- In witness whereof I have hereunto set my hand and seal in the presence of two witnesses.

CORWILL JACKSON. [L.S.]
